SEWING MACHINE CASE.

No. 16,039.

Patented Apr. 14, 1885.

UNITED STATES PATENT OFFICE.

NICHOLAS A. HULL, OF PERU, INDIANA.

DESIGN FOR A SEWING-MACHINE CASE.

SPECIFICATION forming part of Design No. 16,039, dated April 14, 1885.

Application filed February 18, 1885. Term of patent 3½ years.

To all whom it may concern:

Be it known that I, NICHOLAS A. HULL, of the city of Peru, in the county of Miami and State of Indiana, have originated and invented 5 a new and useful Design for Sewing-Machine Cases; and I do hereby declare that the following is a full, clear, and exact description thereof, reference being had to the accompanying photograph, forming a part of this specification.

In the photograph is shown a view in perspective of a sewing-machine provided with a case constructed according to my design. The front portion of this case has a raised panel, 15 A, raised from the main panel B. This raised panel A is divided into a series of smaller panels, a, by a system of angular cuts or grooves, b, extending at right angles and spaced to suit such transfer or ornament as may be desired.

ble to put on the same. Each panel, as will 20 be seen, is beveled on all sides by the angular cuts or grooves.

The case has fluted or beaded corners c, said flutes or beads extending vertically or at right angles with the base of case. 25

What I claim is—

A design for a sewing-machine case, consisting of the raised panel A, divided into a series of smaller panels, a, the main panel B, and fluted or beaded corners c, as shown and 30 described.

In testimony that I claim the foregoing as my own I affix my signature in presence of two witnesses.

NICHOLAS A. HULL.
